CHAIR

Filed Oct. 1, 1929

UNITED STATES PATENT OFFICE

EDWIN T. DEAL, OF ALDAN, PENNSYLVANIA, ASSIGNOR TO THE J. G. BRILL COMPANY, OF PHILADELPHIA, PENNSYLVANIA, A CORPORATION OF PENNSYLVANIA

CHAIR

Application filed October 1, 1929. Serial No. 396,573.

This invention relates to certain improvements in chairs and particularly to those for use in aeroplanes and dirigibles.

One object of the invention is to make a very light chair, and at the same time one which is comfortable and which will accommodate itself to the passenger.

A further object of the invention is to provide means for securing the flexible seat and back section to the frame. The invention also relates to details of construction, which will be described hereinafter.

1. the accompanying drawings:

Fig. 1 is a sectional elevation of my improved chair;

Fig. 2 is a rear view of the upper portion of the chair;

Fig. 3 is a front view of the lower portion of the chair;

Fig. 4 is a detached sectional view on the line 4-4, Fig. 2, showing the method of attaching the free end of the pocket to the upper portion of the seat and back section;

Fig. 5 is a view showing the means of attaching the seat and back section to the frame and the seat proper to the seat and back section; and

Fig. 6 is a view of a modification of the pad at the upper portion of the seat and back section.

1 is the frame of the chair, which is made of metal and preferably of aluminum. This frame has legs 2, arms 3 and a back frame 4. 5 are rungs and 6 is a platform for baggage or other articles. This platform is located directly under the seat section as shown in Fig. 1. 7 is the seat and back section and 8 is the seat cushion.

At the upper end of the back frame is a 40 cross-bar 9, forming, in the present instance, a continuation of the side-bars 10 of the back frame and curved as shown.

The seat and back section 7 is made of any suitable fabric, and the facing material can 45 preferably be of plush or other fabric, while the back is preferably made of a heavy fabric. The upper end of the seat and back section is in the form of a pocket 7a and fits over the cross-bar, as shown in Fig. 1. The free end 50 12 of the pocket is secured to the body portion

of the seat and back section by a snap-fastening 13 of any suitable type. Any suitable type of fastening may be used without detracting from the object of the invention. At the upper end of the seat and back section is 55 a cushion 11 which is located within the pocket 7a and is attached to the seat and back section in any suitable manner. This cushion partly covers the bar as shown.

The lower end of the seat and back section 7 passes around a cross-bar 14 of the frame 1. The cross-bar is secured to the vertical bars of the side frames 15 by brackets 16. The tubular portions of the brackets extend under the cushion, as shown in Fig. 3.

The lower end of the seat and back section 7 extends around the tubular cross-bar 14, and a pocket 7b is formed in the said section 7 for a plate 18. This plate 18 extends from one side bracket 16 to the other and is secured to the webs 17 of the brackets by bolts 19. The lower end of the seat and back section 7 is thus secured firmly to the brackets.

The cushion 8 is detachably mounted on the seat and back section, as shown in Fig. 1, and 75 has a depending flap 20 at its forward end, which extends down past the cross-bar 14 and is secured by snaps 21 to the outer portion of the outer fabric of the seat and back section 7. By this construction the cushion is 80 held firmly in place, but it will yield and accommodate itself to the person occupying the seat.

In some instances a cushion section 11a may surround the cross-bar 9, as shown in Fig. 6, 85 and may be tapered at each end and will conform to the curve of the bar 9.

I claim:

1. The combination in a chair, of a frame having upper and lower cross bars; a bracket 90 at each side of the chair, supporting the lower cross bar, each bracket having a web; a flexible section extending from the upper cross bar and partly around the lower cross bar and having a pocket at its lower edge; a 95 clamping plate extending from one bracket to the other; bolts securing the plate to the webs of the brackets; a cushion section resting upon the flexible section and having a depending flap at its forward end; and means for se- 100

curing the flap to the forward end of the flexible section at the pocket.

2. The combination in a chair, of a frame having upper and lower cross-bars; brackets supporting the lower cross-bar, each bracket having a web; a flexible section extending from the upper to the lower cross-bar and secured to the webs of the brackets; a cushion section resting upon the flexible section and having a depending flap at its forward end; and means for securing the flap to the forward end of the flexible section.

EDWIN T. DEAL.
